UNITED STATES PATENT OFFICE

161,053

PLATE OR SIMILAR ARTICLE

George Rudd, Bedford, Ohio, assignor to The
Walker China Company, Bedford, Ohio

Application March 24, 1950, Serial No. 8,739

Term of patent 14 years

(Cl. D44—15)

To all whom it may concern:

Be it known that I, George Rudd, a citizen of the United States of America, residing in Bedford, county of Cuyahoga, and State of Ohio, have invented a new, original, and ornamental Design for a Plate or Similar Article, of which the following is a specification, reference being had to the accompanying drawing, forming part thereof, wherein,

The sole figure is a top plan view of a plate or similar article, showing my new design.

The dominant features thereof reside in the ornamentation on the surface of the plate as shown.

I claim:

The ornamental design for a plate or similar article, substantially as shown and described.

GEORGE RUDD.
